UNITED STATES PATENT OFFICE.

JOHN G. KOEGLER, OF TOLEDO, OHIO, ASSIGNOR TO INDUSTRIAL RESEARCH CORPORATION, OF TOLEDO, OHIO, A CORPORATION OF DELAWARE.

GAME.

Application filed March 26, 1920. Serial No. 389,031.

To all whom it may concern:

Be it known that I, JOHN G. KOEGLER, a citizen of the United States, residing at Toledo, in the county of Lucas and State of Ohio, have invented certain new and useful Improvements in Games, of which I declare the following to be a full, clear, and exact description.

This invention relates to improvements in games, particularly games in which a roulette wheel or similar rotating element is employed.

The principal object of the invention is the provision of novel means for producing the rotation of a roulette wheel or the like, which shall be extremely simple in construction and devoid of mechanism that is liable to get out of order.

A further object is the provision in connection with a base ball game, of means for determining by chance the plays of the game, which means involve the "throwing" of a ball.

Other objects, and objects relating to details of construction and economies of manufacture, will appear as I proceed with the description of that embodiment of the invention, which, for the purposes of the present application I have illustrated in the accompanying drawing, in which

Figure I is a plan view of a base ball game involving my invention.

Fig. II is a cross section taken substantially on the line II-II, Fig. I.

Fig. III is an edge view of the structure shown in Fig. I.

Similar reference characters refer to like parts throughout the views.

In the drawing, 10 represents a game board, which preferably has imprinted thereon a base ball diamond 11. The board has numerous holes 12 drilled therein for the reception of pegs (not shown) which, as the game progresses, are inserted in the proper holes to indicate the score of the players.

Into one end of the board a socket 13 is sunk and is preferably covered by a transparent sheet 14 of glass or celluloid. From a central position in the bottom of the socket a pin 15 extends upwardly into a correspondingly shaped bore in the bottom of a rotatable element or wheel 16. The latter has an annular recess 17 cut into its upper side with a bottom sloping slightly towards the middle

portion or hub 18. The bottom of the annular recess 17 is divided by means of printed radial lines into sectors 19, in each of which is printed a play that may occur in the game of base ball. In each sector near the hub 18 is a slight depression 20 adapted to receive a ball 21, but not deep enough to retain the ball against any appreciable pressure.

In one edge of the board 10, and for the most part, at least, in a curved edge of said board, is a slot 22 running through the edge wall and into the socket 13. The walls of this slot are inclined inwardly toward each other. The side walls of the slot are spaced far enough apart to enable the finger of the operator to ride thereagainst and extend far enough therethrough to contact with just the right pressure the outer edge of the wheel 16. I have found by experiment that a slot corresponding in length to an arc of approximately 90 degrees produces satisfactory results. It must be at least 60 degrees in order to permit the operator's finger to remain in contact with the wheel long enough to produce rapid motion.

In playing the game the board is held still preferably on a flat surface by one hand of the operator, while a finger of the other hand is placed at that end of the slot furthest from the operator and then drawn rapidly toward him with a snapping action. This causes the wheel to revolve rapidly and the ball 21 then being acted upon by centrifugal force, as well as by frictional contact with the wheel, is "thrown" around with the wheel and out towards the outer wall of the recess 17. It continues its rotary motion even after the wheel ceases to rotate, but finally moves down the inclined bottom surface of the recess towards the hub 18 and comes to rest in one of the depressions 20. The indicia in the corresponding sector determines the play to which the player is entitled. Each player continues playing until three outs are registered against him, when the next player takes his turn, there being an even number of players divided into two teams.

I am aware that the particular embodiment of my invention above described, and illustrated in the accompanying drawing, is susceptible of considerable variation without departing from the spirit thereof, and

therefore I desire to claim my invention broadly as well as specifically as indicated by the appended claims.

I claim as my invention:

- 5 1. In combination, a support, a roulette wheel rotatably mounted upon said support, said support having a wall adjacent the edge of the wheel cut away for a distance corresponding to an arc of approximately ninety degrees, whereby the operator's finger may be placed at one end of said cut-away portion against the side edge of the wheel and moved with a snapping action to the other end of said cut-away portion, thus causing 10 rapid rotation of said wheel.
- 15 2. In combination, a game board having a circular socket sunk therein near one edge of the board, a roulette wheel rotatably mounted in said socket, said board having a slot therein connecting the socket with the said edge, said slot being of a width adapted to readily receive the operator's finger and of a length corresponding to an arc of approximately ninety degrees, whereby rapid 20 rotary motion may be imparted to said wheel 25

by means of a snapping action of the finger.

3. In combination, a support, a roulette wheel rotatably mounted upon said support, said support having a curved wall concentric with the wheel in which is a horizontal slot exposing the edge of the wheel, said slot being inclined inwardly toward the wheel and the parts being so proportioned that the operator's finger while pressing against the sides of the slot will engage the edge of the wheel with a slight pressure only. 30

4. In apparatus of the class described, the combination of a cup-shaped casing, the edge wall of which is cut away to form a radial slot, a plate rotatably mounted within the 40 casing, said plate having an annular channel formed in a side thereof, forming inner and outer walls, and a plurality of depressions adjacent the inner wall, the outer wall of said plate being adjacent to and operably 45 engageable through said slot.

In testimony whereof, I affix my signature.

JOHN G. KOEGLER.
